SHOE FITTER DEVICE

John L. Harris, New York, N. Y.

Application June 29, 1936, Serial No. 87,949

6 Claims. (Cl. 12—128.6)

The present invention relates to a shoe conforming device and it particularly relates to a device for conforming the members of shoes to the irregularities of the feet of the wearers.

5 As shoes are at present manufactured, in mass production, they are usually made according to certain standard lengths and widths.

The feet of many people do not exactly conform to the standard sizes and in many cases there are 10 irregularities and deformities which cause substantial pain and discomfort if the shoes are worn.

Shoes made to order to fit exactly the feet of the wearer are very expensive and usually beyond 15 the means of most people.

Although many devices have been employed for stretching shoes, particularly of the types having two laterally separating jaws, this stretching is applied to the entire shoe and often does not 20 relieve the shoe upper construction sufficiently to enable its conformation to the irregularities and deformities.

In addition, a great many of the stretching devices will distort the shoe or cause damage 25 thereto, shortening the life of the shoe or causing deformities of the shoe in other ways in respect to the feet of the wearer.

It is among the objects of the present invention to provide an improved shoe conforming device 30 which may be readily adjusted or manipulated to conform the upper of the shoe to irregularities or deformities in the feet of the wearer without substantially deforming or damaging the shoe.

Another object is to provide a shoe conforming 35 device which may be readily employed by shoe salesman or wearers to conform shoes to irregularities or deformities in the feet of the wearers, said devices being conveniently utilized incidental to the sale of the shoe to fit the shoe to the feet of 40 the customer.

Other objects will be obvious or will appear 45 during the course of the following specification.

In accomplishing the above objects, according 50 to one preferred embodiment, the device is provided with a wooden form designed to fit a certain size of shoes which wooden form is provided with an expanding plate or similar device on its bottom.

On the top portion is provided a series of protuberances which may be adjustable and removable according to the specific irregularity and deformity in the foot of the wearer.

An expander screw is provided which is adapted 55 to extend through the wooden form and rearwardly therefrom terminating in a handle.

The inner end of the screw element is provided with a cam device which may be forced into contact with the expanding plate to force said adjustable knobs or protuberances into the upper of the shoe and to soften or expand the shoe to 5 correspond to the particular irregularities or deformities in the foot of the wearer.

In the preferred method of constructing these adjustable protuberances the top of the wooden form is provided with a series of recesses which 10 are rigid or of polygonal shape.

The protuberances, on the other hand, are formed of rounded domes or mushroom-shaped plates, to the bottom portions of which are connected pins having corrugations or shapes corresponding to those of the recesses. Thus the bulged or curved plates may be fixedly positioned on the top of the wooden form in a predetermined position to secure the desired conformation.

The rear bottom portion of the shoe form is also 20 preferably provided with a friction grip to hold the device in position in the shoe during the expansion of the plate and the pressure of the conforming knobs into the upper of the shoe.

The above and other objects will appear more 25 clearly from the following detailed description, which when taken in connection with the accompanying drawing, will illustrate preferred embodiments of the inventive idea.

Referring to the drawing:—

Figure 1 is a side view of the shoe with the conformer device of the present application in position therein, the front portion of the shoe being partly broken away.

Figure 2 is a top view of the front portion of the 35 shoe conforming device upon an enlarged scale.

Figure 3 is a longitudinal section upon the lines 3—3 of Figure 2 showing one of the adjustable knobs or mushrooms in the position in which it is to be inserted into the shoe form.

Figures 4, 5 and 6 are respectively side elevational views of the various types of adjustable protuberances which may be employed in connection with the conforming device of Figures 2 and 3.

Figure 7 is an enlarged fragmentary transverse sectional view of the connection between the pin of the adjustable knob or protuberance and recess in the shoe conforming device.

Referring to Figures 1 to 7, the shoe A is provided with an upper front portion B, a sole C and a heel D.

The shoe conformer is provided with a base E made of wood and fashioned to fit one shoe size or a range of sizes, an expanding plate F pivotally 55

connected to said base E, a screw expander G and a plurality of adjustable protuberances H', H² and H³.

The base E terminates at 10 and is bevelled at 11 and is provided with a threaded passage 12 which receives the threaded shank 13 of the device G, said threaded opening 12 and said threaded shank 13 preferably having square threads which are most satisfactory for transmitting sufficient force to expand the plate F away from the base E.

At the forward bottom portion of the base E is provided a recess 14 which receives the knob 15, said knob 15 being fixed by the sleeve 16 and the pin 17 at the end of the shank 13 of the screw device G.

The knob 15 is adapted to abut the inner face 18 of the plate F, which plate F is of the same shape and dimension as the bottom 19 of the base E.

The rear end of the plate is screwed at 20 to a hinge plate 21, which is received in a recess 22 in said expanding plate, said hinge plate 21 being connected by the pivot mount 22 to the fixed plate 23, which is connected by screws 24 to the body of the base E.

On the upwardly sloping portion 25 of the base E is provided the friction grip member 26, which may consist of a piece of corrugated rubber, tacked or adhesively attached to said portion 25, or the surface of the portion 25 may be corrugated or ridged to contain such friction grip.

On the top and on the forward portion 27 of the form E are provided corrugated or ridged holes or recesses 28, 28¹, 28², 28³, 28⁴, and 28⁵.

These recesses have been found to be most satisfactorily arranged if they are positioned in three parallel longitudinal rows, of two or three each, two in each row being shown in Figure 2.

40 In the side rows are respectively the openings 28, 28¹, 28³ and 28⁵. The middle row is provided with the openings 28², and 28⁴, the latter being positioned somewhat forwardly of the corresponding side openings 28, 28¹, 28³ and 28⁵.

45 The shanks 29¹, 29², 29³ are preferably corrugated or ridged to correspond to the recesses 28 to 28⁵, all inclusive, so that they may be placed in any desired predetermined adjusted position to cause satisfactory formation of the shoe upper B.

As shown best in Figure 3, the devices H' to H³ are of mushroom shape with the corrugated pins 29 being attached to the inside center portion of the mushroom plate H', as indicated at 30.

55 If desired, the recesses 28 to 28⁵ and the pins 29¹ to 29³ may be made of hexagonal or square shapes, but this does not give as wide a range of adjustments as the corrugations shown and preferred.

60 The handle 33 attached to the end of the shaft or shank of the screw device G is conveniently shaped for operation by the hand of the customer or shoe salesman.

As indicated in Figures 1 to 3, the mushroom or knobs H' to H³ may be inserted in any suitable position where the shoe member B is to be conformed, and the axis of the mushroom may be suitably positioned by means of the cooperation between the pins 29¹ to 29³ and the recesses 28 to 28⁵ to apply the adjustment to the portion of the upper to be conformed.

By study of the front portion of the foot of the wearer, whether the wearer has hammer toes, bunions, corns or other defects, it is possible to 75 determine the exact position and direction of the

adjustments H' to H³ and then the adjustments may be inserted in position as indicated at Figures 1 to 3.

The collapsed device may be inserted into the shoe, as indicated in Figure 3 and then by turning the handle 33, the knob 15 may be forced against the plate F elevating the base E and forcing the adjustments, mushrooms or knobs H' to H³ into a suitable portion of the shoe upper construction.

It is usually desirable to moisten the portion of the lining or interior portion of the shoe which is to be adjusted by the devices H' to H³ and if desired, said portion of the shoe may also be heated and/or steamed incidental to such adjustment.

The mushrooms or knobs H' or H³ may be made of a wide variety of shapes and sizes and as many recesses such as 28 to 28⁵ may be employed, as found to be convenient.

One of the devices, as shown in Figures 1 to 3 may be utilized over a range of sizes or for one size, as may be desired.

It is to be understood that the form E may be made of molded plastic material such as Bakelite, of metals such as aluminum, of hard rubber or of other suitable materials.

It is apparent that the specific illustrations shown above have been given by way of illustration and not by way of limitation and that the structures described above are subject to wide variation and modification without departing from the scope or intent of the invention, all of which variations and modifications are to be included within the scope of the present invention.

What is claimed is:

1. A shoe conforming device comprising a base member to be inserted in the forward part of a shoe, a separable plate member pivotally attached to the middle portion of the bottom of said base member and extending forwardly to press said base member when separated therefrom against the forward upper portion of the shoe, a cone-shaped wedge member to cause separation between said separable member and said base member, said wedge member being received in a recess in the bottom of said base member and being positioned so that one side thereof will slide longitudinally along the inside face of said separable member, and manually operated means to control said wedge member to separate said separable member and said base member after insertion thereof into the forward part of the shoe, the portion of the bottom of the base member behind said pivoted attachment having a roughened gripping surface, said gripping surface comprising a piece of rubber attached to the base member behind the pivotal attachment and having a corrugated face and the plate being ungrooved.

2. A shoe conforming device comprising a base member to be inserted in the forward part of a shoe, a separable plate member attached to the bottom of said base member to press said base member when separated therefrom against the forward upper portion of the shoe, a cone-shaped wedge member to cause separation between said separable member and said base member, said wedge member being received in a recess in the bottom of said base member and being positioned so that one side thereof will slide longitudinally along the inside face of said separable member, and manually operated means to control said wedge member to separate said separa- 75

ble member and said base member after insertion thereof into the forward part of the shoe, said base member comprising a form of approximately the interior shape of the forward portion 5 of the shoe and said separable member comprising a plate pivotally attached and extending forwardly to the rear part of said base member and having the same outline as the bottom of said base member, the portion of the bottom of 10 the base member behind said pivoted attachment having a roughened gripping surface, said gripping surface comprising a piece of rubber attached to the base member behind the pivotal attachment and having a corrugated face and 15 the plate being ungrooved.

3. A shoe conforming device comprising a base member to be inserted in the forward part of a shoe, a separable plate member pivotally attached to the middle portion of the bottom of 20 said base member and extending forwardly to press said base member when separated therefrom against the forward upper portion of the shoe, a cone-shaped wedge member to cause separation between said separable member and 25 said base member, said wedge member being received in a recess in the bottom of said base member and being positioned so that one side thereof will slide longitudinally along the inside face of said separable member, and manually 30 operated means to control said wedge member to separate said separable member and said base member after insertion thereof into the forward part of the shoe, said manually operated means comprising a threaded shank provided with a 35 handle, and said base member comprising a threaded bore extending obliquely therethrough to receive said shank, the end of said shank being connected to said wedge member, the portion of the bottom of the base member behind said pivoted attachment having a roughened gripping surface, said gripping surface comprising a piece of rubber attached to the base member behind the pivotal attachment and having a corrugated face and the plate being 40 ungrooved.

4. A shoe conforming device comprising a base member to be inserted in the forward part of a shoe, a separable plate member pivotally attached to the middle portion of the bottom of 45 said base member and extending forwardly to press said base member when separated therefrom against the forward upper portion of the shoe, a cone-shaped wedge member to cause separation between said separable member and 50 said base member, said wedge member being received in a recess in the bottom of said base member and being positioned so that one side thereof will slide longitudinally along the inside face of said separable member, and manually 55 operated means to control said wedge member to separate said separable member and said base member after insertion thereof into the forward part of the shoe, said base member being 60

provided with a plurality of corrugated recesses and an adjustable knob member having a corrugated stem to cooperate with one of said recesses to enable expansion of the member of the shoe at predetermined places, the portion 5 of the bottom of the base member behind said pivoted attachment having a roughened gripping surface, said gripping surface comprising a piece of rubber attached to the base member behind the pivotal attachment and having a corrugated 10 face and the plate being ungrooved.

5. A shoe conforming device comprising a form member of approximately the interior shape of the forward portion of the shoe to be conformed, a plate of the same exterior contour 15 as the base of the form and pivotally connected to said form at the rear of the sole of the form, a friction grip positioned on the rear bottom portion of the form where it turns upwardly from the sole, a plurality of holes arranged in 20 rows upon the forward upper portion of the form, where the form corresponds to the toe and instep portions of the shoe, a recess in the bottom of the forward portion of the form to receive an adjustable knob, which is pressed 25 against the forward portion of said plate to separate it from the form, a threaded shank connected to said knob and extending substantially to the rear of the shoe when inserted therein, a handle at the end of said shank, said form 30 having an oblique threaded passage extending therethrough to receive said threaded shank, and a knob or protuberance member fitted into one of said holes to enable expansion of the 35 upper of the shoe at a point corresponding to a deformity or irregularity in the foot of the wearer.

6. A shoe conforming device comprising a form member of approximately the interior shape of the forward portion of the shoe to be 40 conformed, a plate of the same exterior contour as the base of the form and pivotally connected to said form at the rear of the sole of the form, a plurality of non-circular holes arranged in rows upon the forward upper portion 45 of the form, where the form corresponds to the toe and instep portion of the shoe, a recess in the bottom of the forward portion of the form to receive an adjustable knob, which is pressed against the forward portion of said plate to separate it from the form, a threaded shank connected to said knob and extending substantially to the rear of the shoe when inserted therein, a handle at the end of said shank, said form 50 having an oblique threaded passage extending 55 therethrough to receive said threaded shank, and a knob or protuberance member having a non-circular shank fitted into one of said holes to enable expansion of the upper of the shoe at a point corresponding to a deformity or irregularity in the foot of the wearer.

JOHN L. HARRIS.
